SMOKING TUBE

Filed May 21, 1937

UNITED STATES PATENT OFFICE

2,119,198

SMOKING TUBE

Edmund Bruder, Chicago, Ill.

Application May 21, 1937, Serial No. 143,959

11 Claims.

(Cl. 131—22)

This invention relates to improvements in smoking tubes of the type shown and described in my applications Serial Number 20,653 filed May 9, 1935 and Serial Number 83,239 filed June 3, 1936, and one of the objects of the present invention is to improve the construction of such devices.

It has been found that in devices of this character, by reason of the heat generated in the 10 chamber in which the tobacco is consumed, the device becomes heated to such an extent that it is uncomfortable to handle the same. It is therefore another object of the present invention to provide improved means for insulating the smoking 15 or tobacco chamber, thereby reducing to a minimum the heating of the wall of such chamber.

A further object is to reduce the number of parts of the device, thereby not only reducing the weight of the same, but also simplifying the construction thereof.

To the attainment of these ends and the accomplishment of other new and useful objects as will appear, the invention consists in the features of novelty, in substantially the construction, combination and arrangement of the several parts, hereinafter more fully described and claimed and shown in the accompanying drawing illustrating this invention, and in which

30 Figure 1 is a longitudinal sectional view of a device of this character constructed in accordance with the principles of this invention.

Figure 2 is a detail sectional view, on an enlarged scale, taken on line 2-2, Figure 1.
35 Figure 3 is a sectional view taken on line 3-3,

Figure 4 is a detail sectional view taken on line 4—4, Figure 1.

40 5—5, Figure 1, on an enlarged scale.

Figure 7 is a longitudinal sectional view of the
45 can member.

Figure 8 is a detail sectional view of one end of a liner member.

Figure 9 is a sectional view taken on line 9—9, Figure 8.

50 Figure 10 is a side elevation of Figure 8.
Figure 11 is a perspective view of the insulating member.

Figure 12 is a detail perspective view of the locking spring between the cap member and the liner member.

Figure 13 is a detail perspective view of the abutment chamber at the end of the tobacco chamber.

Referring more particularly to the drawing, the smoking tube consists essentially of a body member 15 which is hollow and is constructed of any desired or suitable material and may be of any desired size and configuration. One end of the body member is provided with a portion 16 of a bayonet joint element which is adapted to receive the end 17 of a stem 18. The end 17 of this stem is shaped to form the other element of a bayonet joint, so as to separably lock the body and stem members together. The extremity 19 of the body member contacts a circumferential shoulder 20 on the stem member.

The numeral 21 designates a combined liner and end member which may be constructed of any suitable material and is hollow and provided with a partition 22 extending thereacross and in proximity to one end thereof.

The partition 22 is provided with any suitable number of holes or openings 23 passing therethrough. The outer end of the member 21 may be flanged as at 24 and a circumferential groove 25 is provided in the member and opens through the periphery thereof in proximity to the extremity of the member.

The member 24 is shaped to provide a circumferential shoulder 26, and the body of the member 24 is of an external diameter slightly less than the internal diameter of the body member 15. 30

This member 21 is inserted into the open end of the body member 15 so that the circumferential shoulder 26 will project over and will be in close proximity to the extremity 27 of the body member 15. 35

Arranged in the space between the periphery of the member 21 and the inner face of the body member 15 is insulating material 28 of any suitable material. This insulating material is preferably in the form of a tubular member, as shown in Figure 11, and is provided with a circumferential flange or collar 29, which latter, when the insulating material is in position, will project into the space between the shoulder 26 of the member 21 and the extremity 27 of the body member 15.

If desired, lugs or projections 30 may extend from the extremity 27 of the body member 15 to impale the flange 29 of the insulating material 28, and contact the shoulder 26 of the member 21, to hold the latter against rotation with respect to the body member when the parts are being fastened together.

The body portion of the member 21 is substantially co-extensive with the body member 15 and in this body member 15 adjacent the point of connection of the body member 15 with the stem 5 18, is provided a circumferential shoulder 31.

The body portion of the member 21 is of ductile material so that when the parts 15, 21 and 28 are assembled, the extremity of the body portion 21, which is in proximity to the shoulder 31, is 10 flanged or deflected over the shoulder 31, and with it the adjacent extremity of the insulating material 28 will be flanged over the shoulder 31 as at 32.

Within the stem 18 is a chamber or recess 33 15 which terminates short of the free end of the stem but opens through the other end. The numeral 34 designates a bushing or bearing member having a circumferential flange or head 35 of a diameter greater than the diameter of the bearing member 34. This flange or head 35 engages and rests upon a raised portion at the end of the stem and which raised portion is of a diameter considerably less than the diameter of the adjacent portion of the body member 15, so as 20 to form a space beneath the flange or head 35 for receiving a filter 37 which encompasses the raised portion. This filter 37 may be of any suitable material and is of a diameter substantially co-extensive with the diameter of the flange or 25 head 35.

It will be manifest that the bushing or bearing 34 being screwed into the end of the stem will be held in position and pressure will be relieved from the filter 37, yet the latter will be maintained in 30 position. This filter 37 extends over one or more passages 38 in the stem that open through the stem beneath the filter and also open through the outer extremity of the stem. Within the chamber or recess 33 is arranged a plunger 39 which 35 substantially fills the chamber, and connected thereto is a rod 40 of a diameter considerably less than the diameter of the chamber. This rod 40 projects through the bushing or bearing member 34 and is connected to a follower 41 which 40 is of a size to fit within the tobacco chamber 45 which is formed by the member 21.

The peripheral edge 42 of the follower may be 50 reduced to form a cutting edge and any suitable number of slots or openings 43 may be provided through the follower. At the diametric center 55 of the follower there may be provided a raised or convexed portion 44, for a purpose to be set forth.

This follower 41 is normally urged forwardly 55 in the tobacco chamber preferably by means of a spring 45 disposed beneath the plunger 39 and the end wall of the chamber 33.

Arranged within the tobacco chamber formed by the member 21 and at the outer end thereof is an abutment member 46 provided with a stem 60 47 that is rotatably mounted in a bearing 48 in a cap or end member 49. This stem 47 is provided with a portion 50 which is angular in cross-section and also with a circumferential groove or recess 51 adjacent the angular portion 50.

A spring split washer 52 is provided, which 65 encompasses the stem 47 and enters the recess 51. The washer 52 is of a width to extend across an opening 53 in the partition 22 of the liner and end member and through which opening 53 the stem 47 passes to substantially fill the opening.

The abutment member is provided at its central portion with a convexed surface 54 projecting into the tobacco chamber and is also provided 70 with openings 55 which register with the openings 75

23 of the member 21 as well as the openings 61 in the member 49.

The abutment member is placed in position so that its outer face is disposed in close proximity to the inner face of the partition 22 and is provided with a circumferential groove 56 through the bottom of which groove the spaced slots or openings 55 open.

Projections 57 are provided on the inner face of the partition 22 which enter and move within the groove 56 so as to prevent accumulation of ashes or foreign matter in the groove which would impair the circulation of smoke or air through the openings 55. Similar projections 58 are provided on the other side of the partition 22 and these projections 58 enter and move in a groove 59 in the lower face of a portion of the cap member 49.

This cap member is provided with an open end 60 and through the bottom of this open portion are arranged openings 61. The projections 58 are of such a diameter that when they stand in alignment with the openings 61, there will be a free air or smoke circulating space around the projections 58 and through the openings 61.

The cap member 49 is also provided with a recess 62 which opens through the face that is in proximity to the end of the body member 15 and the wall of this recess is provided with a circumferential groove 63.

The end member 21 above the shoulder 26 is provided with vertical slots 64 which extend through the shoulder 26 and have communication with the groove 25. Two of these slots are preferably provided, one opposite the other, and portions of the walls of the slots intermediate their extremities are enlarged or cut away as at 65.

A locking spring 66 is provided which is preferably of the semi-circular form, the extremities 40 thereof being deflected as at 67 to form spaced parallel portions, and mounted upon these spaced parallel portions 67 are balls or spheres 68.

The body portion of the member 66 is adapted to be seated in the groove 25 in the end member 21, as shown more clearly in Figure 10, while the spaced vertical or parallel portions 67 are seated in the slots 64. The balls or spheres 68 are freely movable upon the portions 67 of the member 66 and enter the enlarged or cut away portion 65 of the slots 64.

When this member 66 is in position, the balls or spheres 68 will be partially seated in the end member 21 and partially seated in the cut away portion 65 of the slots 64 in the end member 21, 55 and will also be partially seated in the groove 63 in the cap member 49 to lock these parts together.

The bottom wall of the slots 64 is cut away as 60 at 69 beneath the balls 68 so that when it is desired to remove the cap 49 from the end member, which may be done by applying force to the cap member while the end member is held, and by exerting said force in a direction lengthwise 65 of the axis of the cap member, the balls 68 by reason of the resiliency of the portions 67 of the spring member 66, will be forced into the cut away portion 69 of the slot 64, so that the balls will be moved out of the groove 63, thereby allowing the 70 parts to be separated. Upon removal of the cap member the balls 68 will assume their normal positions, but when the cap member is replaced the balls 68 will be temporarily depressed back into the cut away portion 69, until the cap is 75

seated, after which the balls will spring out and enter the groove 63.

The tobacco 70 is arranged within the tobacco chamber either loosely or in a carton or wrapper 71 and is placed therein by separating the stem and body members 18—15. The bayonet joint connection between these parts will permit such separation.

When the tobacco is placed within the chamber 10 the stem and body members are then again attached. The spring 45 will force the follower 41 against the end of the supply of tobacco which will in turn be forced against the abutment member 46.

15 As the tobacco is consumed the abutment member 46 may be rotated by grasping the body of the device in one hand and rotating the cap member 49 with respect to the body member. The cap member may be provided with a fluted 20 or serrated periphery 72 provided for that purpose.

By reason of the shape of the abutment member 46 and the follower 41, and particularly the convexed portions 44 and 54, the tobacco will be 25 forced outwardly against the walls of the tobacco chamber, thereby resulting in a better consumption of the tobacco. The ashes are removed by rotating the cap member. As the abutment rotates, the ashes at the lighted end of the tobacco will pass through the openings 55 in the abutment member 46 as well as the openings 23 in the partition 22, and thence through the openings 61 in the cap member 49.

By reason of the insulation 28 the body member 15 will be kept comparatively cool and the temperature thereof will not rise to a point where the device will be uncomfortable to handle.

In the use of the device the smoke is drawn from the tobacco chamber through the openings 43 in the follower 41 into the space between the stem and body members and below the follower 41. From there it will be drawn through the filter 37 and thence through the openings 38 in the stem member.

45 The projections 58 and 57 are of diameters less than the diameters of the openings adjacent which they stand so that no matter what position the projections may assume with relation to the respective openings, the circulation 50 of air through the openings will not be interrupted or cut off.

While the preferred form of the invention has been herein shown and described, it is to be understood that various changes may be made in 55 the details of construction, and in the combination and arrangement of the several parts, within the scope of the claims, without departing from the spirit of this invention.

What is claimed as new is:—

60 1. A smoking tube of the character described embodying a body formed of separable sections, one of said sections being hollow, a hollow member telescoping into the last said section and constituting a tobacco chamber the encompassing 65 wall of which chamber is imperforate, insulating material filling the space between the walls of said hollow section and said hollow member, means securing said hollow member and said insulating material against removal, an apertured 70 wall at one end of said chamber, and means tending normally to urge the tobacco towards said wall.

75 2. A smoking tube of the character described embodying a body formed of separable sections, one of said sections being hollow, a hollow mem-

ber telescoping into the last said section and constituting a tobacco chamber the encompassing wall of which chamber is imperforate, insulating material filling the space between the walls of said hollow section and said hollow member, 5 means securing said hollow member and said insulating material against removal and against rotation in said hollow section, an apertured wall at one end of said chamber, and means tending normally to urge the tobacco towards said wall. 10

3. A smoking tube formed of axially aligned sections separably secured together, a tobacco chamber in one of said sections, an abutment in the chamber, a follower also in the chamber, and means tending normally to move the follower 15 in the chamber to urge the tobacco against said abutment, the said abutment being shaped to urge the tobacco radially against the wall of said chamber.

4. A smoking tube formed of axially aligned sections separably secured together, a tobacco chamber in one of said sections, an abutment in the chamber, a follower also in the chamber, and means tending normally to move the follower in the chamber to urge the tobacco against said 20 abutment, the said follower being shaped to urge the tobacco radially against the wall of said chamber. 25

5. A smoking tube formed of axially aligned sections separably secured together, a tobacco 30 chamber in one of said sections, an abutment at one end of said chamber, a follower in said chamber, means tending normally to move the follower towards said abutment, the proximate faces of said abutment and said follower being 35 shaped to urge the tobacco laterally against the wall of said chamber, and means mounting said abutment for free rotation in said chamber.

6. A smoking tube formed of axially aligned sections separably secured together, a tobacco 40 chamber in one of said sections, an abutment at one end of said chamber, a follower in said chamber, means tending normally to move the follower towards said abutment, portions of the proximate faces of said abutment and said follower 45 being convexed and co-operating to force the tobacco therebetween, against the wall of said chamber.

7. A smoking tube of the character described embodying a body formed of separate sections, a 50 bayonet and slot connection between the proximate ends of the sections for separably securing them together in axial alinement, one of said sections being hollow, a hollow member having a wall at its outer end and open at the other end to constitute a tobacco chamber, and telescoping into said hollow section, a shoulder in the said hollow section, a portion of the wall of said chamber being flanged over said shoulder to secure the parts against separation, there being 55 openings through said end wall, and means for urging the tobacco in said chamber towards said end wall.

8. A smoking tube of the character described embodying a body formed of separable axially aligned sections, one of said sections being hollow 65 and open at its ends, a hollow member having an apertured wall adjacent one end and open at the other end, a circumferential shoulder on said hollow member adjacent said walled end 70 and projecting over the proximate end of said hollow section, said hollow member constituting a tobacco chamber of an external diameter to substantially fill said hollow section but providing a space between its periphery and the wall 75

of said hollow section, a tubular insulating member filling said space, one end of said insulating member being flanged to stand between the said shoulder and the adjacent end of the said hollow section, a shoulder in said hollow section, a portion of the wall of said hollow member being flanged over said shoulder to secure the parts together, and means in the tobacco chamber for urging the tobacco towards the said apertured wall.

9. A smoking tube of the character described embodying axially alined sections separably secured together, one of said sections being hollow and constituting a tobacco chamber, another section constituting a stem, the end of the stem extending across the said chamber, an opening in said stem extending lengthwise thereof and opening through said end, a portion of said end being raised, a bearing in said raised portion, a circumferential flange on said bearing member engaging the end of and projecting beyond said raised portion, a filter between said flange and the adjacent portion of said end and encompassing said raised portion of said end of the stem, and means tending normally to urge the tobacco forwardly in the tobacco chamber, said means embodying a follower in the chamber and a plunger rod connected with the follower and slideable through said bearing and also in the said opening in the stem, the said filter and the said flange being each of a diameter considerably less than the diameter of the space in which they are located, whereby the smoke may be drawn through said filter and also through a passage in the stem over the end of which passage the filter is located.

10. A smoking tube of the character described embodying axially alined sections separably secured together, one of said sections being hollow and constituting a tobacco chamber, another section constituting a stem, the end of the stem extending across the said chamber, an opening

in said stem extending lengthwise thereof and opening through said end, a portion of said end being raised, a bearing in said raised portion, a circumferential flange on said bearing member engaging the end of and projecting beyond said raised portion, a filter between said flange and the adjacent portion of said end and encompassing said raised portion of said end of the stem, and means tending normally to urge the tobacco forwardly in the tobacco chamber, said means embodying a follower in the chamber and a plunger rod connected with the follower and slideable through said bearing and also in the said opening in the stem, the said filter and the said flange being each of a diameter considerably less than the diameter of the space in which they are located, whereby the smoke may be drawn through said filter and also through a passage in the stem over the end of which passage the filter is located.

11. A smoking tube embodying a body formed of separable sections one of said sections being hollow and of a substantial length, a hollow member telescoping into the last said section and constituting a tobacco chamber, said hollow member being open at one end and provided with an imperforate body wall substantially co-extensive with the wall of said hollow section, said member also provided with an end wall having openings therethrough, insulating material filling the space between said body wall and the wall of said hollow section, means for securing the hollow member and said insulation in position, and means tending normally to urge the tobacco toward said end wall.

EDMUND BRUDER.
